UNITED STATES PATENT OFFICE.

SIMON E. SCHROEDER, OF MINIER, ILLINOIS.

GEARING.

1.153.715.

Specification of Letters Patent. Patented Sept. 14, 1915.

Application filed January 8, 1913. Serial No. 740,810.

To all whom it may concern:

Be it known that I, SIMON E. SCHROEDER, citizen of the United States, residing at Minier, in the county of Tazewell and State 5 of Illinois, have invented certain new and useful Improvements in Gearing; and I do hereby declare that the following is a full, clear, and exact description of the invention, which will enable others skilled in the art 10 to which it appertains to make and use the same:

This invention relates to washing machines and particularly to that type having a vertical oscillating shaft including an agitator at its inner end.

An object of the invention is to provide a simple and effective means of low cost for imparting an oscillating movement to the said shaft.

20 Another object is to provide in connection with a continuously operating portion and mechanism to operate the said shaft, a clutch of separable portions one portion carried by the said continuously operated portion and the other by the said mechanism.

The invention, besides these objects, relates to certain details of construction as will be pointed out herein aided by the accompanying drawing in which,

30 Figure 1 illustrates a tub and my invention in connection therewith. Fig. 2 is an elevation of a portion of a clutch and a rock arm. Fig. 3 shows a second clutch portion in perspective. Fig. 4 is a plan of certain operating parts, and Fig. 5 is a plan of a modified form of parts shown in Fig. 1.

It is my purpose as above stated to provide mechanism for oscillating the shaft and its agitator and employ a simple form of 40 mechanism for that purpose and likewise to introduce clutch portions to operate the shaft from a continuously moving part, said clutch portions being so constructed that they will be disengaged when the cover or 45 lid of the tub which carries the shaft and agitator is lifted, said clutch portions automatically engaging when the lid or cover is again closed.

50 A indicates a tub mounted on any suitable platform B and having a stationary top portion C to which is hinged the usual raisable lid or cover D. Centrally of the said lid or cover D is a shaft E having a suitable bearing therein but not shown. From the inner 55 or lower end of the shaft is suspended any usual agitator F the particular form of

which is immaterial since it forms no part of the present invention.

Secured on the upper or outer end of the shaft E is a pinion G. In mesh with it is a gear-segment H mounted in any suitable manner on an arm K secured upon the lid D, and whose outer end extends slightly beyond the edge of the tub. The said outer end of the arm is provided with a portion 60 L having a vertical bore M, Fig. 2, forming a bearing for a short shaft N secured to whose upper end is a cross-head O at its middle. Connected to each end of the cross-head is a rod H' each of which is also connected with the segment gear H, the two rods thus employed lying parallel to one another.

The lower end of the shaft N carries a clutch portion consisting of a disk Q from 75 which depends a pair of spaced lugs or fingers R preferably pointed at their ends.

S is a bearing secured on the side of the tub through which extends a vertical shaft T. Its upper end carries a plate U provided 80 with a pair of notches V lying at diametrically opposite sides as shown in Fig. 3 or, at least, in the proper position to receive the lugs or fingers R referred to, the engagement of one of the fingers and one of 85 the notches being shown in Fig. 1. The plate U is held at such a height that the plate Q of the upper clutch portion will lie upon or in close proximity to it when the lid is closed.

90 The lower end of the shaft T receives an oscillating movement which may be imparted to it by any desired mechanism. As an instance of the mechanism that may be employed I have shown in broken lines in Fig. 95 1 a beveled gear 2 which is carried at the under side of the platform B. It rotates in a horizontal plane and in mesh with it is a pinion 3 fixed on a shaft 4 which has suitable bearings at 5, for example, upon said 100 platform, the shaft being provided with a driving wheel 6. The lower end of the shaft T is provided with a crank-arm 7, Fig. 4, to which is pivoted one end of a connecting rod 8 the other end of which has pivotal connection with the gear 2.

105 It is now observed that continuous rotation imparted to the shaft 4 results in a continuous rotation of the gear 2 and through the connecting rod 8 the shaft T will be 110 oscillated together with the clutch portion, the plate U. This in turn oscillates the

other clutch portion Q R and the cross head O as well as the segment-gear H through the parallel rods H'. The shaft E and its agitator F thus receive a like motion. When the lid or cover D is raised the lugs or fingers R are disengaged from the notches V, the mechanism of said lid or cover then remaining idle. Since the plate U continues in action its notches V must at some time be brought into register with the lugs or fingers R which rest upon the plate U when the lid has been let down and said lugs or fingers will then enter said notches. I may employ other means of transmitting motion from the shaft N to the shaft E and Fig. 5 is an example of this. A sprocket wheel 9 may replace the gear, its shaft in this instance being indicated by E'. Secured to each end of the cross-head, indicated in said figure by O', is a sprocket chain 10 which extends around the sprocket wheel and engages its teeth. It is evident that the cross head will impart motion to the sprocket wheel which is the oscillating movement. Other arrangements producing the same result may also be used though that shown in Fig. 1 is the preferred form.

Without confining myself to the exact structure shown and having described my invention, I claim:—

1. In a driving mechanism for washing machines, the combination with a main support and a movable support coöperating therewith, of an actuating shaft mounted on said main support, a member mounted on said movable support in alinement with said actuating shaft, a driven shaft also mounted on said movable support, connecting means between said driven shaft and said member, and a clutch having coöperating separable members one on said actuating shaft and one on said member.

2. In a driving mechanism for washing machines, the combination with a main support and a movable support coöperating therewith, of an actuating shaft mounted on said main support, means for oscillating said actuating shaft, a member mounted on said movable support, a driven shaft also mounted on said movable support, connecting means between said driven shaft and said member, and a clutch having one part mounted on said actuating shaft and a coöperating part mounted on said member, said parts being in engagement in one position of said movable support and separated in another position of said movable support.

3. In a driving mechanism for washing machines, the combination with a main support and a movable support coöperating therewith, of an actuating shaft, a driven shaft mounted on said movable support, a drive gear pivotally mounted in operative relation to said driven shaft, operating parts connected to said drive gear one on each

side of its pivot, an operative connection between said actuating shaft and said operating parts for moving said parts simultaneously in opposite directions, and means for oscillating said actuating shaft.

4. In a driving mechanism for washing machines, the combination with a main support and a movable support hinged thereto, of an actuating shaft mounted on said main support, a member mounted on said movable support, a separable clutch connection between said actuating shaft and said member, a driven shaft mounted on said movable support, a pinion carried by said driven shaft, a drive gear pivotally mounted adjacent said pinion and in mesh therewith, a cross-arm connected with said member, and an operating device extending from each end of said cross-arm to and connected with said drive gear on opposite sides of its pivot.

5. In a driving mechanism for washing machines, the combination with a main support and a movable support coöperating therewith, an actuating shaft mounted on said main support, a member mounted on said movable support, a separable clutch connection between said shaft and said member, a cross-arm mounted on said member, a driven shaft mounted on said movable support, a pinion carried by said driven shaft, a segmental drive gear pivotally mounted adjacent said pinion and in mesh therewith, and an oscillating connection between said cross-arm and said drive gear comprising two rods, each of which is pivotally connected to an end of said cross-arm and to said drive gear on the corresponding side of its pivot.

6. In a device of the class described the combination of an upright driving shaft, a support movable relatively to said upright shaft, operating mechanism on the movable support, and separable power transmission parts intermediate of the power shaft and operating mechanism, said parts being arranged to be engaged when the support is in the normal operating position and disengaged when the support is moved from the operating position.

7. In a device of the class described the combination of a main frame, power driving mechanism under the main frame, an upright shaft extending above the main frame and operated by the power transmission mechanism, a support movable relative to the main frame, operating mechanism on the movable support, and separable devices intermediate of the upright shaft and the operating mechanism, said devices being arranged to be in engagement when the movable support is in the normal operating position and adapted to be disengaged when the support is moved from said position.

8. In a device of the class described the combination of a driven member having re-

versing movement, a support movable relatively to said member, an operating mechanism on the support, and separable parts connecting said member and the operating mechanism, said parts being arranged to be engaged when the support is in the operating position and to be disengaged when the support is moved therefrom.

9. In a device of the class described the combination of a main support, an operating shaft thereon, a support movable relatively to said operating shaft, an operating mechanism on the movable support, a driving shaft on said main support connected with the op-

erating mechanism, said operating shaft being arranged in alinement with the operating shaft and separable power transmission members intermediate of said shafts, said members being arranged to be in engagement when the support is in the operating position and adapted to be disengaged when the support is moved from said position.

In testimony whereof I affix my signature, in presence of two witnesses.

SIMON E. SCHROEDER.
